(57) **CLAIM**

The ornamental design for a collapsible container, as shown and described.

DESCRIPTION

FIG. 1 is a top perspective view of a design for a collapsible container.

FIG. 2 is a bottom perspective view of FIG. 1.

FIG. 3 is a top view of FIG. 1.

FIG. 4 is a bottom view of FIG. 1.

FIG. 5 is a right side view of FIG. 1.

FIG. 6 is a left side view of FIG. 1.

FIG. 7 is a front view of FIG. 1; and,

FIG. 8 is a rear view of FIG. 1.

1 Claim, 6 Drawing Sheets
